UNITED STATES PATENT OFFICE

123,507

DESIGN FOR A BASE FOR RAILWAY CROSSINGS

Benjamin Cullen Monroe, Tuscola, Ill.

Application September 13, 1940, Serial No. 95,009

Term of patent 14 years

To all whom it may concern:

Be it known that I, Benjamin Cullen Monroe, a citizen of the United States, residing at Tuscola, in the county of Douglas and State of Illinois, have invented a new, original, and ornamental Design for a Base for Railway Crossings, of which the following is a specification, reference being had to the accompanying drawing, forming part thereof, wherein:

Figure 1 is a plan view of a base for a railway crossing showing my new design; and

Fig. 2 is a perspective view looking from above and toward one corner thereof.

I claim:

The ornamental design for a base for a railway crossing, as shown.

BENJAMIN CULLEN MONROE.
